CLAIM

The ornamental design for a memorandum input and output terminal, as shown and described.

DESCRIPTION

FIG. 1 is a top front and right side perspective view of a memorandum input and output terminal showing our new design in the opened position;
FIG. 2 is a top plan view thereof;
FIG. 3 is a front elevational view thereof;
FIG. 4 is a right side elevational view thereof;
FIG. 5 is a rear elevational view thereof;
FIG. 6 is a left side elevational view thereof;
FIG. 7 is a bottom plan view thereof;
FIG. 8 is a top front and right side perspective view thereof shown in the closed position;
FIG. 9 is a top plan view thereof;
FIG. 10 is a front elevational view thereof;
FIG. 11 is a right side elevational view thereof;
FIG. 12 is a rear elevational view thereof;
FIG. 13 is a left side elevational view thereof; and,
FIG. 14 is a bottom plan view thereof.
